(57) **CLAIM**

The ornamental design for an electrical connector, as shown and described.

DESCRIPTION

FIG. 1 is a front, right side and top perspective view of an electrical connector in accordance with a first embodiment of my new design;

FIG. 2 is a rear, right side and bottom perspective view thereof;

FIG. 3 is a front elevation view thereof;

FIG. 4 is a rear elevation view thereof;

FIG. 5 is a left side view thereof, a right side view being a mirror image thereof; and

FIG. 6 is a top plan view thereof, a bottom plan view being a mirror image thereof.

FIG. 7 is a front, right side and top perspective view of an electrical connector in accordance with a second embodiment of my new design;

FIG. 8 is a rear, right side and bottom perspective view thereof;

FIG. 9 is a front elevation view thereof;

FIG. 10 is a rear elevation view thereof;

FIG. 11 is a left side view thereof, a right side view being a mirror image thereof;

FIG. 12 is a top plan view thereof; and,

FIG. 13 is a bottom plan view thereof.

Portions of the drawings depicted in broken lines form no part of the claimed design.
